STOP MECHANISM FOR WEB FEED

Serial B. Otis, Chicago, Ill., assignor to The Wallace Press, Chicago, Ill., a corporation of Illinois

Application March 31, 1941, Serial No. 385,997

3 Claims. (Cl. 197—133)

This invention relates to typewriting and printing machines, motor driven and more or less automatic in operation, particularly manifolding machines employing long webs made up of successive forms that are fed to the machine by pin-type feed devices engaging perforated feed bands on the margins of the webs.

The main object of this invention is to provide an improved form of stop mechanism for automatically stopping the machine when the feed of the paper web is interrupted by breakage of the web or by an obstruction to the web feed and before the operating mechanism can be injured by excessive strain.

A specific embodiment of this invention is shown in the accompanying drawings, in which:

Figure 1 is a perspective view of the web feeding and stop mechanism mounted on an automatic typewriting machine, the latter being for the most part broken away.

Fig. 2 is a section of the manifolding web feeding mechanism taken on the line 2—2 of Fig. 1.

Fig. 3 is a sectional detail taken on the line 3—3 of Fig. 1.

Fig. 4 is a detail of a gear train with some related parts shown in section, taken on the line 4—4 of Fig. 1.

Fig. 5 is a detail of a portion of the pin-type feed mechanism illustrating a possible entanglement of the manifold web that might occur if one or more of the sheets happens to be torn.

Fig. 6 is a detail of the mechanism that controls the stopping of the machine when the manifold web becomes jammed.

Fig. 7 is a sectional detail of the same showing a suitable form of trip mechanism in its normal driving position.

Fig. 8 is a similar detail showing the same parts in position for actuating the stop switch.

In the form shown in the drawings, the machine, represented generally by the numeral 10, is driven by an electric motor 11 and may be of a well-known type in which the printing mechanism is controlled by punched control cards in which apertures in the card are employed for actuating automatic mechanisms of the machine to print corresponding information upon the manifold forms by means of type members that rise through the opening 12 and cooperate with a platen 13. For the sake of simplicity of the drawing, these type members are not shown, since they form no part of the present invention.

The safety stop mechanism of the machine is controlled by a switch key 14 and the mechanism of the machine is such that when said key

14 is depressed, the machine will instantly stop. The web feeding mechanism comprises a lower feed bed made up of spaced generally parallel plates 15 along which the manifolding web 16 is fed to the platen 13. The web then passes between the platen and the paper guide rollers 17 and then over an upper feed bed comprising spaced guide plates 18 from which it is fed in the direction of the arrow 19 to a suitable conveyor or magazine, not shown.

The supporting framework for this paper feed mechanism comprises side frame members 20 and 21 connected by transverse rods and bars 22, 23, 24 and 25. The middle set of guide plates 18 and 15 are fixed in position on said rods and bars. The right-hand and left-hand paper feed assemblies are each slideable as a unit and are relatively adjustable to suit any desired width and position of the manifold webs.

20 In the form shown, the feed pins 26 in each such assemblage are carried by an endless belt 27 mounted on a pair of sprockets 28 and 29 as appears from Fig. 2. The idle sprockets 28 are carried by spindles 30 and the driven sprockets 29 are carried by the squared drive shaft 31.

Each of the pin-feed assemblies comprises a pair of side plates 32 between which the sprockets 28 and 29 and their belts 27 are mounted and these plates 32 are rigidly attached to the respective one of the guide plates 18 of the upper feed bed. These assemblies are supported by a shaft or bar 33 in addition to the squared drive shaft 31 by means of which the sprockets and belt are driven. Both of these paper feed assemblies are adjustable along the shaft 33 and are fastened by set screws, or other fastening devices, which engage flat areas 34 on said shaft.

Also carried by the side plates 32 is a guide plate 35 for holding the lower run of the manifolding webs against the lower feed bed plates 15. This guide plate 35 is located a sufficient distance below the feed belt 27 to be clear of the pins 26 on the lower flight of the belt. The upper plate 18 is, however, located so that the feed pins 26 will project through a slot 36 into engagement with the pin holes in the manifolding webs.

50 A guide shoe 37 is hinged to one of the check plates 32 in each feed assemblage and is shiftable on its hinges into and out of position for engaging the feed bands of the paper webs as shown in Figs. 2 and 1 respectively. The shoe 37 is slotted at 38 to accommodate the movement of the pins 26 throughout that part of their path during which they engage the paper web.

55 A clutch 40 connects two sections of the drive

shaft 31 so that the two feed belts may be adjusted relatively to each other for proper engagement with the perforations of the respective feed bands of the manifold webs.

The gear train, illustrated in Fig. 4, connects the squared drive shaft 31 with a gear 41 on the spindle 42 of the platen roller, so that the pin-feed devices will be driven in exact timed relation to the platen.

Gear 44 is loosely mounted on a reduced cylindrical end portion 45 of the shaft 31 and has an integral clutch member 46 on one side that contacts with a clutch member 47 fixed on shaft 31. One of these clutch members has an arcuate depression 48 to receive a correspondingly formed cam projection 49 on the other.

A ball bearing 50 for the cylindrical end 45 of the shaft 31 is mounted in a bearing cup 51 attached to the side frame 20 in position to be engaged by a hub extension 52 of the gear 44 on one side and by a shiftable plate 53 on the other side. This shiftable plate 53 is slidably mounted on a pair of studs 54 which carry a head 55 in which is seated a compression spring 56 which normally urges the plate 53 toward the left, of Figs. 7 and 8, and thus indirectly holds the clutch elements 48 and 49 in normal engagement as in Fig. 7. An adjusting screw 57 is threaded in the head 55 and carries a lock nut 58 whereby the tension of the spring 56 may be adjusted to adjust the driving strain limit for the paper feed.

The plate 53 carries an arm 59 which extends into the housing 60 of a quick-throw electrical switch, indicated at 61, which may be of any appropriate construction for being actuated by very slight movement of arm 59. In the form shown, the contact elements of the switch are housed in an insulated casing from which an operating stud 62 projects into contact with the spring arm 63 which extends in a position to be engaged by the arm 59.

A two-wire electric cord 64 connects the switch contacts with an electromagnetic motor or relay 65, Fig. 3, which comprises a magnet 66, an armature arm 67 which is pivoted at 68, and has a finger 69 that extends across the top of the machine stop key 14. A compression spring 70 normally holds the finger 69 released from the key 14 and a stop pin 71 on the arm 67 adjustably limits the throw of the arm 67 under the action of compression spring 70. A button 72 operates the switch 73 which connects the operating circuit of the relay with a power line, indicated by terminals 74.

A second two-wire conductor cord 75 connects the relay 65 with a second stop switch 76 which is positioned and arranged to stop the machine 10 when a break in the paper webbing occurs. These conductor cords 64 and 75 are connected together and to a line cord 77 so that either or both will actuate the relay.

Preferably the safety key 14 is arranged so that the machine 10 can operate only when said key 14 is elevated and the arm 69 with its relay is so arranged as to hold said key 14 depressed whenever current is supplied to the relay by closing stop switches 61 and 76 and said switches are closed.

The switch 61 is closed when the parts of its respective operating mechanism are in the relative positions shown in Fig. 7, and is open when they are in the positions shown in Fig. 8.

Similarly the switch 76 is normally closed when its operating mechanism is in the position in which it is shown in Fig. 2. In this arrangement the switch pin 77 of the switch 76 is actuated by 75

an arm 78 pivoted at 79 and carrying at its end a roller 80 that rides on the under side of the manifold web 16 and the shield or web guide plate 35 is provided with an aperture 81 in registering position with the roller 80.

The arm 78 is normally urged across the path of the webbing, either by a spring that normally urges the switch pin 77 outwardly from its casing 76 or by a spring coiled around a pivot pin 79 as is apparent without illustration.

In operation the superimposed webs of manifold paper with their interleaved carbons are threaded through the machine in the manner illustrated in Fig. 2 so that the pins 26 of the feed mechanism register with perforated feed bands of the manifold webs and draw the webbing around the platen where it is printed upon and advanced by intermittent feeding operations in synchronism with the movements of the platen roller 13.

If a breakage occurs in the webbing or the end of the webbing arrives at a point past the roller 80, said roller will rise through the opening 81 and close the relay circuit by means of the switch 76 which will actuate the stop key 14 so as to stop the machine.

Similarly, if the manifold web becomes torn or buckled so as to offer unusual resistance to the feeding thereof by means of the pin band mechanism, this resistance will be transmitted to the shaft 31 and will permit the feed gear 44 to ride out of its clutching engagement with the clutch member 47, as illustrated in Fig. 8.

The camming action of the opposed clutching surfaces 49 and 48 will shift the gear 44 to the right of Fig. 8 and cause the shifting of the finger 59 so as to close the circuit at the switch 61 and actuate the relay to stop the machine.

It is obvious that a normally closed electric circuit may be used for controlling the stop mechanism in place of the normally open circuit that has been herein described. In such case the stop switches 61 and 76 would be connected in series with each other at the connector 80.

Although but one specific form and arrangement of each of the features of this invention is herein shown and described, it will be understood that numerous details of the construction shown may be altered or omitted without departing from the spirit of this invention as defined by the following claims.

I claim:

1. A printing machine with platen feed having a key for operating its control mechanism, in combination with an auxiliary paper feed device having electromagnetic means for shifting said key, and a safety switch controlled by the paper in said auxiliary feed device for actuating said electromagnetic means.

2. The combination with an automatic type-writing machine having a platen feed and provided with a shiftable key for operating its control mechanism, of a manifold web feeding mechanism having means for feeding a manifold web to and from the platen, an electromagnetic motor associated with and having means arranged to actuate the shiftable key to stop the printing machine when the electromagnetic motor is operated, a switch electrically connected with the motor and located adjacent the web feeding mechanism, and means carried by the web feeding mechanism and responsive to breakage of the web for actuating the switch to operate said motor to stop the machine in event of break-

age of the paper and when there is no paper to be written upon.

3. The combination with an automatic typewriting machine having a platen feed and provided with a shiftable key for operating its control mechanism, of a manifold web feeding mechanism having means for feeding a manifolding web to and from the platen, an electromagnetic motor associated with and having means arranged to actuate the shiftable key to stop the printing machine when the electromagnetic motor is operated, a switch electrically connected

with said motor and located adjacent the means for actuating the web feeding mechanism, and a clutch incorporated in said actuating means and responsive to increase in resistance to the movement of said web for actuating the switch to operate said motor and stop the typewriting machine in event of jamming of the paper through accidental defects in the paper whereby injury to the delicate mechanism of a typewriting machine is prevented.

ERIAL B. OTIS.
